UNITED STATES PATENT OFFICE.

WILLIAM H. SCHULTE, OF HOPEDALE, ILLINOIS.

GRAIN-SEPARATOR.

SPECIFICATION forming part of Letters Patent No. 469,827, dated March 1, 1892.

Application filed November 10, 1891. Serial No. 411,470. (No model.)

To all whom it may concern:

Be it known that I, WILLIAM H. SCHULTE, a citizen of the United States, residing at Hopedale, in the county of Tazewell and State 5 of Illinois, have invented certain new and useful Improvements in Grain-Separators; and I do hereby declare the following to be a full, clear, and exact description of the invention, such as will enable others skilled in the art to 10 to which it appertains to make and use the same.

The invention relates to grain-separators which have rotary wire screens, such a one being described in Patent No. 215,078, granted to Sturgeon on the 6th of May, 1879.

15 My invention consists of the particular means by which I raise or lower one end of the screen-shaft, so as to regulate the inclination of the screen to suit the grain or seed which is to be separated; also, the particular 20 means which are employed by me to jar or shake the reel when so desired.

Figure 1 of the drawings is a vertical longitudinal section of the separator; Fig. 2, a detail vertical sectional view of the device 25 for raising or lowering the discharge end of the reel or screen shaft. Fig. 3 is a detail view of the hand-piece, together with its connections, which are in section; Fig. 4, a detail side elevation of the knocker and the 30 strip against which it turns, and Fig. 5 a detail view of the shaft and showing the annular groove therein.

In the drawings, A represents the discharge 35 end of the case, slotted at *a* to allow the flat part *b* of the hand-piece B to pass therethrough, as it also passes through the slot *c* of an outside plate C, which is made fast to case end A. On this plate C is made a rack or series of notches on each side of the slot *c*. The piece B has a tubular portion *b'*, whose 40 shoulders abut against plate C, while through the tube extends a rod D, which has a finger-disk *d* on the outside end and a cross-pin *d'* on the inner end. Around the rod and between its ends is arranged a spiral spring E, which holds the cross-pin in the rack or 45 notches on plate C. On the inner end of the hand-piece B is secured a vertical slide F, which is moved in the guides G G on the 50 case end A. At the top of this slide is an open bearing to receive one journal of the screen-shaft H. When it is desired to change the inclination of the screen, one finger is pressed on the disk *d*, while the slide F is car-

ried up or down to make the adjustment. 55 The spring on rod D will then draw the cross-pin *d'* in the opposite grooves of plate C and thus hold the slide securely.

On the shaft H, near the hopper, I place a polygonal disk to turn with the shaft against 60 the strip J. As the polygon I turns it jars the screen, so as to dislodge the seeds which may stick in the interstices of the wire reel, the shaft H rising in the slot *a'*. The knocker may or may not be used, as the shaft H has a 65 groove *h*.

When it is desired to use the knocker, move the hopper end or the elevated end of shaft up to the polygonal disk, when the latter will strike or jar the reel or screen. The shaft-groove *h* receives the bearing of slide F, or the screen, which is always on an incline, would slip back. The wire screen is made somewhat shorter than the inside of the case, which allows the higher end of the reel to be 70 moved up, so as to be locked on the bearing of slide F. Without making the groove *h* in the shaft I could not use the knocker; but with it I can operate the knocker or not, as circumstances make it expedient or otherwise. 75 I have, however, tested the whole invention in a full-sized grain-separator, and both features thereof have been found to work well. Hence I have deemed it but right that I should obtain protection under the patent law 80 for what must inure to the benefit of the public.

Having thus described all that is necessary to a full understanding of my invention, what I claim as new, and desire to protect by Letters Patent, is—

In a grain-separator, the combination, with the end A, having the vertical slot *a*, of the hand-piece B, flat at *b* and tubular at *b'*, the outside plate C, having slot *c* and notches on 90 each side thereof, the rod D, having a disk *d* at one end and a cross-pin *d'* at the other, the spiral spring E around said rod, and the slide F, having an open bearing at the top, all substantially as shown, and for the purpose 95 specified.

In testimony whereof I affix my signature in presence of two witnesses.

WILLIAM H. SCHULTE.
